JOEL W. SMITH, OF ARDMORE, OKLAHOMA.

LOCKING MEANS FOR FREIGHT-CAR DOORS.

1,308,646.

Specification of Letters Patent.

Patented July 1, 1919.

Application filed January 30, 1918. Serial No. 214,456.

To all whom it may concern:

Be it known that I, JOEL W. SMITH, a citizen of the United States, and a resident of Ardmore, in the county of Carter and State of Oklahoma, have invented a new and Improved Locking Means for Freight-Car Doors, of which the following is a full, clear, and exact description.

My invention relates to locking means for freight car doors, and particularly relates to locking means involving a series of locking elements disposed about the door at opposite sides and at the top and bottom thereof and controlled by the unitary operating means.

The general object of the invention is to provide a lock for freight car doors of the indicated character improved in various particulars with respect to the form and arrangement of the locking elements and the actuating means therefor.

Reference is to be had to the accompanying drawings forming part of this specification in which similar reference characters indicate corresponding parts in all the views, it being understood that the drawings are merely illustrative of one example of the invention.

Figure 1 is a transverse vertical section taken through the door in the closed position;

Fig. 2 is a front elevation showing the door in the closed position, parts being broken away and others in section;

Fig. 3 is a horizontal section, with the door in the closed position;

Fig. 4 is a view similar to Fig. 3 but showing the door in the open position;

Fig. 5 is a detail in transverse vertical section on the line 6—6, Fig. 2, showing a detail of the locking means with the co-acting locking elements disengaged;

Fig. 6 is a view similar to Fig. 5 with the coacting locking elements engaged;

Fig. 7 is a perspective view of one of the rockable locking elements;

Fig. 8 is a detail in sectional plan view, the view being given to show a latch device for holding the door in open position.

In carrying out my invention in accordance with the illustrated example the car 10 may be of any standard make. In the door opening a metal frame 11 is provided. The numeral 12 designates the car door which in the illustrated example is guided at the

top in an overhanging rail 13 and at the bottom in a rail 14. The upper rail may be fixedly secured in any suitable manner, there being shown an angle bar 15 for the purpose. I prefer to arrange the lower rail 14 to be raised or lowered for which purpose the rail is pivotally held in end brackets 16 by bolts 17 to swing vertically. In the raised position the rail 14 is supported by swinging brackets 18 pivotally supported at their inner ends in keepers 19 on the car frame. Thus, when the door is opened for the unloading of the freight, the rail 14 may be lowered out of the way by swinging the brackets 18 downward against the car side, permitting said rail to drop. At the upper end the door 12 has headed pins 20 which move in corresponding T-shaped slots 21 in the under side of the upper rail 13, while at the bottom of the door plain pins 22 are provided thereon, movable in slots 23 in the upper side of the lower rail 14. As seen in Figs. 3 and 4, the slot 23 at the end adjacent to the door opening extends obliquely so as to guide the door laterally to and from the door opening as the door is brought into or out of register with said opening. There is also a transverse, slightly curved slot member 25 extending from the slot 23 to take the adjacent pin 22 of the door while the pin 22 at the opposite side of the door follows the oblique portion 24 of the slot. In opening the door from the position shown in Fig. 3 the right hand side as represented in said figure is swung outward until the pin 22 at that side reaches the straight portion of the slot 23. Then as the door is moved longitudinally of the car the left hand pin 22 follows the slot 24. In order to hold the door in the open position a latch hook 26 is provided as best seen in Fig. 8. Said latch is pivoted at one end as at 27 to the inner side of the rail 14 so that when the latter is lowered, the latch 26 will be disposed in position for an oblique slot 28 in one edge thereof to engage the adjacent pin 22 of the door. The latch has a bent end 29 or equivalent finger-hold. In order to give the door a tight fit the same is formed at the inner side with an inwardly disposed flange 30 which is received in a groove or recess 31 formed in the frame 11. The above described devices form no part of my improved locking mechanism but are desirable in connection with a door embodying said locking mechanism.

In connection with the main door 12 I have shown an auxiliary door opening and door with a telescoping chute or spout for loose grain or the like. Thus, the numeral 5 32 indicates a transverse opening in the door which may be rectangular as shown. In said opening a suitable bushing 33 is provided which is cast integral with the inner side of the door. A telescoping section 34 10 is movable transversely on the bushing 32 and is provided with a flange 35 at the outside of the door. A chain 36 prevents the entire detachment of the spout section 34 which may be brought outward and tilted 15 as indicated in Fig. 2. The auxiliary door opening 32 is closed by a door 38 which has at the inner side a groove 39 for receiving a flange or bead 40 on the main door whereby to effect a tight closure. The door 38 is 20 hung on a cranked hinge rod 41, the upper and lower cranked ends of which turn in keepers 42 on the main door, and said auxiliary door is provided with suitable locking means, there being shown a hinged hasp 43 25 adapted to engage over a staple bar 44 having a series of holes therein to receive a padlock indicated.

I provide a system of coacting locking elements within the door between the inner 30 and outer sides thereof, the door being made hollow to accommodate said locking elements and their operative means. A series of rockable locking elements 45 are provided at the opposite sides and at the top 35 and bottom of the door, and these are adapted to engage coacting elements 46 preferably in the form of plates set into the door frame 11. The rockable elements 45 are formed with worm threads to engage or dis- 40 engage similar threads in the elements 46. I provide suitable means to simultaneously dispose the locking elements 45 in locked or unlocked relation to the coacting elements 46 for which purpose in the illustrated ex- 45 ample said locking elements 45 are carried by arms 45^a which are pivoted at one end as at 45^b on links 47 which in turn are pivoted as at 48 to slides 49 movable on fixed guide rods 50 disposed horizontally 50 at the top and bottom and vertically along the sides of the door within the same. As seen best in Fig. 7 each locking element 45 has a flat side 51, the remaining portion being formed with worm teeth to engage simi- 55 lar teeth in the fixed elements 46, and said element 45 has a longitudinal bore 52 there- in to receive a pin 53 which is supported at its inner end in the inner side of the door or main casting of the door and at its outer 60 end in a facing plate 54 on the door at the front. The front plate 54 is held in fixed position by spacing blocks 55 and suitable securing means such as pins or bolts 56, (see Fig. 2). In addition to the pin hole 65 52 and pin 53 for the turning of the locking

element 45, the said element has a pin hole 45^c receiving a pin 45^d extending through the carrying arm 45^a to insure the rocking of said element when the arm 45^a is actuated.

For simultaneously operating the several slides 49, a spindle 57 is provided extending through the front 54 of the door whereby to be turned from the exterior and on said spindle is a bellcrank lever 58, one arm of which is connected to the bottom slide 49 by a link 60, and the other arm is connected by a link 59, to one vertical slide 49. A second link 61 connects the bottom slide 49 with a second bellcrank 62, the other arm of which is connected by an upright link 63 with the adjacent upright slide 49 and said link 63 connects by a link 64 with the adjacent side arm 45^a. A similar system of links and levers connects the upright slides 49 with the upper horizontal slide, there being shown at the top bellcrank levers 65 corresponding with the levers 58, 62 and a system of links corresponding with the described system at the bottom of the door. 90 The numeral 66 indicates studs or blocks on which the bellcrank levers other than the lever 58 are mounted. From the foregoing it will be clear that a turning of the spindle 57 will engage or disengage the respective 95 locking elements 45, 46. In order to provide additional locking means the spindle 57 has a hasp lever 67 for turning the same, said lever being disposed at the outside of the door, and being adapted to engage a 100 staple 68 or the like whereby a padlock 69 may be employed to lock the staple lever and spindle 57 against movement. The numeral 70 represents a handle on the door.

In addition to the tight closure effected by the flange members 30 and mating grooves 31, a further means to insure the tight closure consists of edge flanges 54^a at the sides of the facing plate 54 (Figs. 3 and 4), adapted to fit over the front ex- 110 tensions 11^a on the door frame 11, said ex- tensions projecting forwardly beyond the side of the car.

I wish to state in conclusion that although the illustrated example constitutes a 115 practical embodiment of my invention, I do not limit myself strictly to the mechanical details herein illustrated, since manifestly the same can be considerably varied without departure from the spirit of the invention as defined in the appended claims.

Having thus described my invention I claim as new, and desire to secure by Letters Patent:—

1. The combination with a structure having a door opening, of a door to close said opening, rockable locking elements on the door, said elements being each in the form of a mutilated worm, and coacting locking elements presenting teeth adapted for en- 125 130

gagement by the rockable elements, and means to actuate said rockable elements to engage or disengage said fixed elements.

2. A locking means for doors including a rockable element in the form of a mutilated worm, a relatively fixed element having teeth corresponding with the worm element, and means to actuate said rockable element to engage or disengage the fixed element.

10 3. The combination with a door, of a series of locking elements each in the form

of a worm having a flattened side, arms carrying said elements, fixed guide rods adjacent to the respective elements, slides on said guide rods, lever and link connections 15 between the respective slides, means to actuate one of said levers, and relatively fixed coacting locking elements with which the rockable locking elements are adapted for engagement.

JOEL W. SMITH.
